RAZOR

Russell Pelton Harshberger, Pasadena, Calif.

Application May 14, 1937, Serial No. 142,708

9 Claims. (Cl. 30—44)

This invention relates generally to razors, and more particularly to improvements in razors embodying a motor mechanism, and to razors of such character in which a vibratory motion or impulse is imparted to the cutting element without directly driving the same, and the description which follows is therefore specifically addressed to these embodiments of the invention.

Razors embodying a vibratory action of the above character in general create the same by a fixedly positioned unbalanced weight caused to travel in a rotary path describing a plane which is normal to the plane of the cutting element and in a direction paralleling the cutting edge thereof. Such operation requires a definite positioning of the blade to obtain expected results. There is substantially only a single position of the cutting element that is proper. Thus razor devices of this character do not have universal application as a combining element with razor guards of all types now in use. For example one type of razor guard has a screw stud for connecting it with the razor stem. In no two cases are the threads in the same relative position at the beginning and end thereof. Thus if secured to a device of the above character the guards would take different positions with respect to the plane determined by the rotating unbalanced weight, and in all probability neither would assume a final position best for receiving the reciprocatory impulses. In other words the present day mechanism is not suited to razor assemblies where the cutting edge of the cutting element may take a varied position in the plane of such element around the stem of the razor.

Further, the rotary unbalanced weight is generally carried in the same frame supporting the driving mechanism and its shaft is in a position, if projected to the plane of the cutting element, normal to the cutting edge. This construction requires that the vibratory action be transmitted through the driving mechanism and frame, to the shell carrying the frame and therefrom to the cutting element and its supporting head. A considerable loss of energy must be expected by the time the vibrations reach the desired place. It is believed that the mass of the frame etc. has a damping action upon the vibrations.

Proposals to drive the razor head carrying the razor guard and cutting element, by a cam to avoid loss of energy through dampening, require much more power to drive and readily jam in operation.

In addition the fixedly positioned rotating unbalanced weight has been relied upon as the sole

source of governing action for the consumption of power from the drive spring as well as for determining the rapidity of vibrations. Light weights have permitted too much speed, too rapid vibrations and result in a quickly run down motor. Heavy weights require and consume too much power and cause too much shake in their uneven operation.

Moreover, in spring motor mechanisms of the character that may be used in the present invention, and which are typified by those of my prior Patents 1,760,496 granted May 27, 1930; 1,890,647 granted December 13, 1932; 1,404,693 granted January 24, 1922; and 2,056,186 granted October 5, 1936; the proper setting of the main drive gear or wheel relative to its mating pinion is of considerable importance, in view of the large amount of power imparted through the main gear or wheel as well as the ease by which variable assembly produces large friction losses and wear and great strain in the cooperating parts. Bevel gears have been the most difficult to use and spur gearing has been far superior but in either case the mating of the gear and pinion has generally been a blind operation, which although properly guided, has not always given the best setting of these main gears or wheels for most efficient operation.

According to the present invention the disadvantages above enumerated as well as many others are largely overcome, and a practical and efficient razor of vibratory character embodying novel features also applicable to other types of motor driven razors is obtainable.

The invention in one aspect comprises a razor in which is provided an unbalanced weight preferably driven by the high speed output of a spring operated motor mechanism and which describes an arc or circle determining a plane lying substantially parallel to the plane of the cutting element, or subtending an angle thereto not unfavorable to the features to be described. Such an unbalanced weight imparts a vibratory or reciprocating action to the cutting element irrespective of the position of the cutting edge in the plane of the cutting element or blade. Moreover I believe it imparts to each point on the cutting element a continuous motion determining a path which I term elliptical or egg shaped. I have found that it produces particularly efficient shaving. According to my device the cutting element or blade is believed to be under the continuous influence of the unbalanced weight and without a substantially dead period in the cycle of reciprocating action. In order to further improve the

shaving operation I contemplate in combination with the above vibratory action, better motor speed and impulse control. This I accomplish by combining with the inertia effect of the unbalanced weight a friction brake device operating substantially concurrently with the unbalanced weight. Thus I obtain a balance of weight and speed that gives proper shaking action and long operation of the spring motor. It will be understood that my novel control is not only useful with vibratory razors but may also improve the character of operation of other motor driven razor mechanisms, for example those indicated in my prior patents aforesaid.

A device made according to my invention may be used as a stem for all types of safety razor guard and clamp combinations now in the market employing blades having one or two cutting edges, it being contemplated to provide a universal means of mounting these to the head of my device or provide specific means for each type of combination. For example, in one type of razor guard construction where the blade clamp carries a screw stud that passes through the blade and guard, I may provide a suitably threaded hole in the head end of my device to receive the stud. On the other hand where the clamp has a threaded hole I may provide a threaded stud or projection to engage therewith. Similarly other types of guards may be suitably secured to my device. Likewise my invention is operable with the character of blade mounts disclosed in my copending application Ser. No. 89,327 filed July 7, 1936.

The invention is found to be particularly effective when the unbalanced weight and/or friction governing means is carried by the head of my razor device so that the impulses emanating therefrom are directly imparted to the cutting element without being transmitted, for example, through the gear train frame and the razor shell with a substantial loss of energy and driving force. The unbalanced weight is preferably mounted according to my invention, in the razor head and driven by a simple coupling with the main gear train, that is automatically aligning.

These and other objects and features of the invention will more fully appear from the following description and the claims, and the accompanying drawing forming a part thereof, which however, must be considered as merely illustrating a preferred embodiment and in no way limiting the invention to the embodiment shown and described. It will be understood that certain aspects of my invention are applicable to different types of razors, and their broad application is contemplated. It will also be understood that all modifications including features of construction, combination of elements and arrangements of parts as may be within the spirit of the invention are contemplated.

In the drawing herein similar parts are designated by similar numerals.

Fig. 1 is an axial sectorial view through a device embodying the features of the invention and is taken as indicated by the line 1-1 Fig. 4.

Fig. 2 is a fragmentary view of the device with the casing partially in axial section, said device being viewed at right angles to the line of section in Fig. 1 and shows a typical razor guard and clamp in detached position.

Fig. 3 is a transverse section taken along line 3-3 of Fig. 1.

Fig. 4 is a transverse section taken on the line 4-4 of Fig. 1.

Fig. 5 is a fragmentary sectional view of a modification showing a method of attaching the razor guard to the razor head.

Referring more particularly to Figs. 1-5 of the drawing, 10 designates a casing preferably tubular in shape to the upper end of which is fixed a head 11, to which may be fastened a blade supporting bed 12. It will be understood that the blade supporting bed may be an integral part of the head 11 where desired. A blade 13 may be mounted on said bed in a definite relation and is held in place by a cap or cover element 14. The blade may have one or two cutting edges as desired. The lower end of the casing 10, carries a handle, generally designated as 15, adapted for rotational movement relative to the casing. The handle is preferably bi-sectional comprising a cup-shaped end section 16, and a tubular inner section 17 preferably fashioned as at 18 for screw-threaded union. The inner section 17 is reduced to provide a portion 19, the tubular outer end of which is adapted to abut against the end of the casing 10, in which position the outer surface of the casing 10, and restricted portion 19 are substantially flush or continuous. A locking member 20, forming a press fit as at 21 with the inner surface of the casing 10, extends within and beyond the reduced portion 19 of the inner section 17 and has an outwardly extending annular flange 22 thereon arranged to substantially abut against the shoulder 23 which is provided by the reduced portion of the inner section. The handle is in this manner, mounted for relative rotational movement on the casing by the confinement of the portion 19 between the end of the casing 10, and the flange of the locking member 20. By making the locking member a press fit with the casing 10, a better assembly is possible since it is fixed for all time and cannot be shifted by tinkering or in operation. Moreover parallel rubbing faces are thus assured for the winding handle. It is quite important that there should not be much end play in the handle and the indicated method of assembly permits the proper amount of end play to be secured. It will be noted that the locking member 20 has a portion of considerable length pressed with the tubing 10, and its upper end acts as a limit stop for the power transmitting mechanism. Furthermore the parts 10, 17, and 20, form a single unit for plating and finish and such may be accomplished economically and efficiently and without involving additional assembly.

Within the handle 15 is a source of power such as a coil spring motor designated generally as 24. This spring is preferably enclosed, or at least partly so, by a sleeve 25, having an inturned projection 26 thereon engaging the outer end of the spring. An annular rib 27 on the sleeve is bindingly engaged between a shoulder 28, formed on the end section 16, and the end of inner section 17. Thus the outer end of the spring is secured to the handle for winding the spring in the rotation of the handle relative to the casing. The inner end of the spring is drivingly connected to a stub drive shaft 29, by pins 30 and 31. This shaft at one end is journaled in a bearing 32 provided in the end wall 33 of the end section 16. The opposite end of the stub shaft 29 is carried in a tubular sleeve 34 which serves the function of a main drive element and has another function to be presently described.

One end of the sleeve 25, extends beyond the side of the spring and has an inturned flange

35 thereon which, when the parts are assembled lies substantially adjacent to the flange 22 on the locking member 20. The flange 35 is fashioned to provide a series of internal, radially facing ratchet teeth 36 (see Fig. 3). A pawl 37 is mounted for movement about a pivot 38 stationary with respect to the locking member 20 and comprising a stud having a flanged head, a reduced annular portion passing through the ratchet 37 and a further shank passing through a spacing washer 38a and secured in the locking member 20 as by a drive fit and riveted over upon the inside. The pawl is urged as by a spring 39 toward the ratchet teeth 36 and is so arranged that it permits movement of the handle 15 relative to the casing 10 only in a spring winding direction. If desired an additional pawl and spring may be provided in symmetrical position to that shown in Fig. 3 but 180 degrees apart.

Whilst a single motor spring is specifically disclosed it will be understood that a multiple tandem arrangement is herein contemplated depending upon the length of time desired for operation of the parts. Multiple motor spring units of a suitable character are disclosed in my prior patents aforesaid.

The driven movement of the shaft 29 is transmitted to the impulse producing mechanism carried by the head 11. The preferred form of power transmitting mechanism involves a train of gears, generally indicated at 40 (Figs. 1 and 2), intermediate the spring drive shaft 29 and the weight driving pinion 79 and by which the relatively slow rotation of the shaft 29 may be increased to a high speed of rotation of the shaft 52. An understanding of the relationship of the various gears in the train will be facilitated if the manner of mounting the gears in the casing 10, is first described. Thus bearing plates 42 and 43 are maintained in spaced relation by an interposed partially cylindrical spacer 44, formed of somewhat resilient material and having opposed lugs 45 (see Figs. 1 and 2) which are engageable in receiving notches or recesses provided in the peripheries of the plates 42 and 43. The resiliency of the spacer 44 maintains the parts in substantially rigid assembly which assembly may be more permanently established if desired in any suitable manner.

The head 11, which is hollow, is preferably turned straight as at 46 and is a push fit into a similar straight tubular surface in the end of the casing 10. A shoulder 47 is provided on the head 11 to provide a positioning abutment for the head 11 as well as to enable abutment of the tip of the head 11 against the bearing plate 42 when the parts are assembled. It will be understood that the turned portion of the head 11 aforesaid may be threaded if desired and fit a similar thread in the casing 10. However, with the present invention, it has been found that assembly of the gear mechanism past a smooth surface is to be preferred. The other bearing plate 43 is engaged, to prevent displacement of the bearing plate assembly, by the locking member 20 which as previously stated has a press fit with the casing 10. Thus the location of the gear train mechanism is definitely established and there are no so-called floating parts to be engaged in making the assembly. The lugs 45 of the spacer 44 are of sufficient length to also engage receiving notches or recesses in the end of the locking plate 20 adjacent to the bearing plate 43. In addition the lugs at the opposite end of the spacer 44 may if desired engage the portion 46 of the head 11. In

such case the portion 46 will preferably not be threaded. In the manner presented the bearing plate assembly is securely locked in the casing and relative rotational movement therebetween is prevented. The bearing plate 43 is further provided at its centre with a projecting pin stud 48 shouldered slightly where it enters the plate 43 and made rigid therewith. The projecting tip of the pin stud is conical shaped for the reasons hereinafter explained.

Considering the relationship of the several gears comprising the gear train, the numerals 52, 53, and 54 designate shafts which extend between and are journaled in the bearing plates 42 and 43 in substantial parallelism with each other and with the axis of the casing 10. A feature of the invention relates to the method of carrying the internal gear 55 and its connection to the spring motor mechanism. For convenience in manufacture and assembly the mounting of the gear 55 preferably comprises a cup shaped member 56 carrying a rabbeted groove 58 on its inner surface to receive the gear 55. A flanged clip 59 encircles the cup shaped member with the flange overlying the outer face of the gear 55 to secure it rigidly in place. The gear 55 engages a pinion 60 (Figs. 1 and 2) which is rigidly fixed to an end of the shaft 54 extending through and beyond the bearing plate 43 (Fig. 2). The cup shaped member 56 is provided with a hub 57 which projects on both sides of the rib portion of the cup and is carried by the pin stud 48 secured in the bearing plate 43. The inner hub portion is of sufficient length to space the internal gear member with operating clearance from the bearing plate 43 and to align in proper running mesh the gear 55 and its spur pinion 60. The outer portion of the hub 57 is formed with a cross slot the function of which will be further described. Moreover, the overall length of the hub 57 is also less than the length of the stud pin 48. It should be evident that by the described manner of construction and assembly an accurate and definite mating of the gears 55 and 60 is assured. The gear 55 is coupled to the spring motor mechanism by the sleeve 34 forming the upper part of the stub shaft 29. This sleeve fits over the pin stud 57 sufficiently to assure good centering, and is provided with a pair of projecting lugs which mate with the recesses in the hub 57 and thereby provide a resilient coupling with the spring motor. Thus no twisting or bending stresses are transmitted to the gear cup 56 but such tendencies are absorbed by the pin stud 48. In order to aid in assembly the locking bushing 20 has its inner turned portion provided with an opening slightly larger than the sleeve 34 so that the coupling end may be readily picked up by the conical end of the pin stud 48. It should be understood that the cup shaped member 56 and the sleeve 34 may comprise a single unit though for the above reasons this is not preferred.

Between the plates 42 and 43, the shaft 54 has a gear 61 fixed thereto and engaging a pinion 62 rotatably mounted on the shaft 53. The pinion 62 is rigid with a gear 63 which in turn meshes with a pinion 64 carried by and rotatable relative to the shaft 54. A gear 65 is rigid with the pinion 64 and drivingly engages a pinion 66 mounted on and rotatable relative to the shaft 53. A gear 67 rigid with the pinion 66 is in mesh with a pinion 68 (Fig. 1) fixed on the shaft 52. Movable with the pinion 68 is a gear 69 fixed to and carried by the end of shaft 52 journaled in and extending through the bearing plate 42.

The governing means by which the driven speed of the shaft 52 is controlled, and the mechanism by which the vibratory or reciprocating impulses are imparted to the razor is carried in the head 11 and comprises a simple mechanism which may be readily assembled in itself as well as in the whole unit and can readily be adjusted for proper operation. Referring particularly to Figs. 1 and 4, a fixed overhanging shaft 11 having a long support in the projection 12 within the head 11, supports a relatively rotatable sleeve 73, which carries a governor plate 74, herein having the form of a flat disk. The disk is of slightly less diameter than the internal diameter of the head and the disk has a pivot pin 75 fixed thereon in pivotal support of a centrifugal weight 76. A stop 77 limits the radially inward swing of the weight 76 and the weight is resiliently urged in this direction. Preferably the means for so urging the weight comprises a spring, for instance a coil spring 78 which extends from the weight to a spring stud, in the present instance the limit stop pin 77. Fixed to the sleeve 73 is a pinion 79 which engages the output gear 69 of the gear train unit. Thus when the pinion 79 is driven by the energy furnished by the spring motor mechanism the weight 76 revolves about the fixed shaft 11 producing an unbalanced effect which imparts a vibratory or pulsating effect in the form of a reciprocating motion taking a characteristic elliptical path. Obviously the greater the unbalanced mass that is rotated the more accentuated the effect will be and co-extensive therewith the greater will be the consumption of power which will also be comparatively irregular. I have found that it is desirable not to have an excessive unbalance and furthermore to have a smooth and uniform speed operation of the unbalanced weight so that the resulting action will be regular in its effect. It is for these reasons that I preferably employ a pivot weight in combination with a spring for example as disclosed in the drawing, viz., a tension spring 78. The tension of the spring is of course a force which must be overcome before the unbalanced weight 76 can swing radially outward as the disk 74 rotates. When the disk 74 is driven at or above a certain predetermined speed the unbalanced weight 76 swings radially outward to bring wearing nib 80, preferably formed of leather or other suitable friction material, into frictional wiping engagement with the adjacent wall of the head 11, the friction of which engagement is sufficient to retard the driven speed of the disk 74 and maintain such speed at or below a predetermined rate. Thus a balance can be obtained between speed and unbalanced mass whereby the motor energy may be efficiently conserved and a smooth and regular vibratory action imparted to the head. The spring 78 also reduces the strain upon the disc bearing by reducing the amount of rotating mass necessary to obtain good speed control. At the same time the unbalanced mass is thereby made such as to be most efficient for vibratory or reciprocatory action.

It is contemplated that the shaft 11 may be rotatable instead of fixed in the head 11 in which case a suitable bracket may be extended from the head 11 to provide a second bearing. Also more than a single pivoted weight may be employed and where such weights are to provide the unbalanced mass one weight shall exceed the mass of the other to provide the desired unbalance. The unbalance may also be created by

proper shaping of the disk or plate 74 carrying the speed governing elements. Where two weights are employed a spring control of the character disclosed in my prior Patent 2,056,186 5 aforesaid may be used. It will be noted that the unbalanced weight has the effect of transmitting the vibratory action directly to the head 11 so that there is no loss of this effect by absorption in the razor stem.

10 A further novel feature of the invention resides in the simple assembly between the head unit carrying the governor and unbalanced weight mechanism, and the gear train assembly. The fixed shaft 11 carrying the pinion 79 is preferably positioned in the head 11 so as to be centrally located with respect to the shell 10 and the turned shoulder 46 of the head 11. The center distance between the shaft 52, carrying the gear 69, is set to obtain proper mesh between the gear 69 and pinion 79 in assembly. Thus it should be noted that it is merely necessary to engage the fully assembled head 11 with the shell 10 and engagement of the gear and pinion will take place irrespective of the position of the gear 69 about the pinion center. Moreover the device will function properly irrespective of such positioning.

20 Ordinarily no difficulty will be encountered in causing the gear and pinion to mesh; however, to insure mesh if the teeth are not in the exact mating relation the teeth on the leading face of the gear or pinion or both may be slightly chamfered. Preferably the gear 69 is caused to rotate by imparting power to the gear train unit and when the head is assembled in position the gear 69 picks up the pinion 79.

25 The assembly above described comprising the spring motor mechanism, gear train mechanism, and head mechanism may constitute a complete unit by itself and be used as the stem for any safety razor blade or cutting element attachment heretofore in use. In Figures 1 and 2, I have disclosed one of the conventional cutting unit assemblies, consisting of a guard 12 having at 30 each of its edges the conventional tooth formation, a double edged blade 13 supported by the guard and a clamping plate 14 slightly curved so as to clamp the blade close to its cutting edges. In these figures it will be seen that the 35 element 14 is provided with a fixed stud 85 having a threaded tip and which passes through the blade 13 and guard 12. For a razor cutting element unit of this character the head 11 of the stem unit of my invention is provided with a 40 suitably threaded hole 86 in which to screw the stud 85 thereby clamping the blade and forming a complete razor unit. The member 12 or 14 generally includes blade guide pins, not shown, one on either side of the stud 85 in the direction 45 of length of the guard 12. It is to be understood that where the type of razor unit used with the stem of my invention does not include a stud 85 but has the clamp plate 14 threaded, a double ended stud may be provided to fit the threaded opening in the head 11 and that in the 50 part 14. Obviously a separate head 11 may be provided having a projected stud member integral with the head if desired.

55 In Fig. 5, I have disclosed a preferred form of arrangement wherein a guard 87 is carried by an annular projection 88 on the stem of head 11. The guard is similar in all general respects to those in use with the exception that it is positioned to be freely rotatable with respect to the 60 projection 88 and the projection 88 is provided

with a threaded hole 89 which is centrally located and having a thin rim which is spun over to prevent the guard 87 from falling off. The guard 87 is somewhat conical where it fits over the projection 88 and its overall thickness is greater than the maximum extension of the projection 88 in its final position so that when a clamp plate, for instance, that designated by 14 in Fig. 2, is assembled with the guard not only is the blade clamped in position but also the guard 87 is firmly clamped and drawn against the shoulder 90 of the head 11A. It will be understood that the razor guard and clamp assemblies here disclosed are merely typical and that provision may readily be made for the assembly of my stem unit to the guard or bed of any blade unit. Furthermore I desire it understood that a blade unit employing the centering features of my prior application Serial #89,327 filed July 7, 1936 can be included.

In order to lock the head 11 with respect to the shell 10, particularly where a straight shoulder 47 is provided, or even where the same is threaded, I preferably provide a tube 91 extending flush with the outer face 46 of the shoulder 47 and located near the lower end of this shoulder on a line through the center thereof and which has a press or drive fit therewith. Preferably where the shoulder 47 is threaded, the length of the tube 91 is such as to limit its projection into the wall of the head 11, as far as the base of the thread so as not to interfere with screwing the head 11 in position in assembly. The shell 10 is provided with suitable openings of the same size as the inner dimension of the tube 91 which openings coincide in position with the corresponding openings in the annular surface 46. When assembly of the head 11 and shell 10 is completed a pin 92 is driven through the tube flush with the outer surface of the shell 10 and prevents, thereby, removal of the head 11, thereby reducing tinkering tendencies.

In Fig. 1 a simple means for supplying lubricant to the operating parts of the device is shown. This may comprise a mass 93 of lubricant absorbing material, such as a felt strip wound spirally and located in the annular recess provided therefor in the head 11. Suitable means is preferably provided so that the felt strip will not shift from this position during operation of the razor. An additional mass 94 held by retainer 95, of lubricant absorbing material may be provided in the clamp plate 20 in the space between its inner wall and the coupling 34. This material when thoroughly saturated with lubricant provides an internal supply of lubricant which is available to all parts of the mechanism.

In the operation of the razor mechanism the operator rotates the handle 15 relative to the casing 10 to place the spring 24 under tension. This tension being delivered to the main drive shaft 29 and coupling sleeve 34, rotates said sleeve and shaft and through the agency of the interposed gear train drives the pinion 79 at a greatly increased rate of speed. This causes the unbalanced weight 76 to provide a continuous cycle of impulses giving to the cutting element 13 a characteristic elliptical path of movement. Obviously the unbalanced weight and its companion brake shoe 80 provide a governing means to hold the driven speed of the unbalanced weight at or below a predetermined maximum rate so that the impulses imparted to the cutting element 13 will be most effective.

From a consideration of the foregoing pre- 75

ferred embodiments of my invention it will be seen that I have provided a novel and improved form of razor embodying features that constitute a distinct improvement over the prior art, and which embody many novel features of construction and assembly. It will be understood by those skilled in the art to which the invention appertains that the disclosed embodiments may be varied and/or combined in numerous ways without departing from the spirit of the basic features I have presented. I therefore desire to secure for myself all modifications and alternative constructions falling within the spirit and scope of the invention as expressed in the foregoing specification and I desire that the invention be construed to cover all equivalents and as broadly as the claims taken in conjunction with the prior art may allow.

I claim:

1. In a safety razor in which a rapid oscillatory motion is imparted to the razor blade by vibratory impulses, the combination with a casing having a blade carrying head at its upper end and a spring motor adjacent its lower end, of a rotatable unbalanced weight adapted to produce vibratory impulses imparting motion to said blade, a relatively short supporting member for said weight positioned between said head and spring motor, said supporting member being held from displacement relative to said head and projecting downwardly therefrom and mounting said weight for rotation, and gear driving means powered by said spring motor to rotate said unbalanced weight at high speed.

2. In a safety razor in which a rapid oscillatory motion is imparted to a cutting blade by vibratory impulses, the combination with a razor body having a blade carrying head at its upper end, and enclosing motor power means, of a rotatable unbalanced member adapted to produce vibratory impulses imparting motion to said cutting blade, a relatively short supporting member having its upper end held from displacement relative to said head and having its lower end free, and suspending said member downwardly from said head, and gear driving means powered by said motor power means to rotate said unbalanced member at high speed.

3. In a safety razor in which a rapid oscillatory motion is imparted to the razor blade by vibratory impulses, the combination with a razor body enclosing a motor and having a blade carrying head at its upper end, of an unbalanced rotatable member downwardly suspended from said head and including a movable weight hinged on said member and responsive to centrifugal force, and drive means powered by said motor to rotate said unbalanced member at high speed, said unbalanced member adapted to produce vibratory impulses when rotated whereby to impart motion to said blade.

4. In a safety razor in which a rapid oscillatory motion is imparted to the razor blade by vibratory impulses, the combination with a razor body enclosing a spring motor and having a blade carrying head at its upper end, of a rotatable member, supporting means projecting downwardly from said head and mounting said rotatable member, a hinged weight responsive to centrifugal force, mounted on said rotatable member and producing unbalance of said member when rotating whereby vibratory impulses may be produced to impart motion to said blade, said weight also substantially controlling the rate of said impulses,

and drive means powered by said spring motor to drive said member at high speed.

5. A safety razor as claimed in claim 4 including a spring member opposing outward motion of said hinged weight.

6. In a safety razor in which a rapid oscillatory motion is imparted to the razor blade without mechanically driving the same, the combination with a casing having a blade carrying head secured to its upper end and having a handle enclosing a spring motor secured to its lower end, of a rotatable unbalanced member including a hinged weight responsive to centrifugal force, downwardly suspended from said head and surrounded by a wall of said head, said hinged weight having spring means resisting its outward movement and rotatable in a plane generally paralleling that of the blade and said weight having braking means to engage the surrounding wall surface of said head when rotating, and drive means powered by said spring motor to rotate said unbalanced member, said unbalanced member adapted to produce vibratory impulses at a substantially controlled rate when rotated whereby to impart motion to said blade.

7. In a safety razor, the combination of a hollow casing, an annular surface at the upper end of said casing, a blade carrying head engaged with said annular surface, a support in said casing carrying power transmitting mechanism, a spur gear projecting from said mechanism support on the side of said head, and having its axis paralleling the axis of said annular surface but offset with respect to said axis, a spur pinion having its axis coincident with that of said annular surface, and suspended from said head by a member projecting downwardly from said head, said

pinion engaging said spur gear, and an unbalanced weight also mounted on said member and suspended from said head thereby, said weight being rotatable by said spur pinion and adapted to produce vibratory impulses imparting motion to a blade carried by said head and without mechanically driving said blade.

8. In a safety razor in which a rapid oscillatory motion is imparted to a cutting blade by vibratory impulses, the combination with a razor body having a blade carrying head at its upper end and enclosing motor power means, of a rotatable unbalanced member adapted to produce vibratory impulses imparting motion to said cutting blade, an elongated bar-like supporting means having its upper end fixed from displacement relative to said blade carrying head and having its lower end free, and suspending said unbalanced member downwardly from said head, and driving means powered by said motor power means to rotate said unbalanced member at high speed.

9. In a safety razor in which a rapid oscillatory motion is imparted to the razor blade by vibratory impulses, the combination with a razor body enclosing a motor and having a blade carrying head at its upper end; of an unbalanced rotatable member downwardly suspended from said head and including a pinion and a weight responsive to centrifugal force to render said rotatable member unbalanced, and gear drive means powered by said motor and engaged with said pinion to rotate said unbalanced member at high speed, said unbalanced member adapted to produce vibratory impulses when rotating whereby to impart motion to said blade.

RUSSELL PELTON HARSHBERGER.
